FIG 2

INVENTOR
G. S. DYER

By *Mr. Wright*,

ATTY.

UNITED STATES PATENT OFFICE.

GUY S. DYER, OF LAYTON, UTAH.

LEACHING-MACHINE.

1,353,463.

Specification of Letters Patent. Patented Sept. 21, 1920.

Application filed August 27, 1919. Serial No. 320,085.

To all whom it may concern:

Be it known that I, GUY S. DYER, a citizen of the United States, residing at Layton, in the county of Davis and State of 5 Utah, have invented new and useful Improvements in Leaching-Machines, of which the following is a specification.

The present invention relates to improvements in leaching or diffusing apparatus.

10 One object of the invention is to provide an apparatus of this character in which the process of diffusion or leaching will be continuous and in which there will be avoided the necessity of devoting particular care to 15 avoid cutting the material into portions some of which would be so small as to pack, and, consequently, prevent free circulation of the liquid therethrough.

In the accompanying drawing, Figure 1 20 is a broken side view of my improved apparatus; Fig. 2 is a cross-section on the line 2—2 of Fig. 1.

I have devised my improved apparatus 25 specifically for the purpose of extracting sugar from beets, cane, grapes, and other saccharine bearing material and I will, therefore, describe it with reference thereto. It is to be understood, however, that it can be applied to any material containing substances which it is desired to leach, as, for 30 instance, oil from grape seeds, tannic acid from grape residues, etc.

The material is fed through an opening 1 into one end of a cylindrical chamber 2, 35 which can rotate by means of circular rails 3 therearound, traveling upon flanged rollers 4, mounted in suitable bearings 5, said body is caused to so rotate by means of a gear ring 6 formed therearound, engaged by 40 a pinion 7 of a shaft 8 rotating in bearings 9, and driven by any suitable source of power, not here shown. Said cylindrical chamber is divided into compartments 11, five of which are here shown, although in 45 practice, I generally use more, as seven or eight. These compartments are formed by annular plane transverse partitions 12, the outer edge of each partition being connected in any suitable manner with the cylindrical 50 body 2. Extending in front of each partition are two diametrically opposite shifter plates 13, which are perforated and extend at an angle to the partition, so that the front edges of said plates, having regard to the 55 direction in which the cylinder rotates, are closely adjacent to said partition, while the

rear edges are at a considerable distance therefrom. The inner portions of said shifter plates extend inwardly, through the openings in the partitions, as shown at 14. 60 These shifter plates tend to convey the material from the outer to the inner portion of the cylinder and cause it to pass through the holes in the partitions. They are perforated so as to strain the material while so 65 shifting it from one compartment to the next, the strained liquor flowing through said perforations into chambers 16 between the shifter plates and the partitions.

I also provide vanes 17 extending inwardly from the wall of the chamber, said vanes being arranged on said wall in a general longitudinal direction but obliquely to the axis of the cylinder, said vanes as well as the plates 13, serving to move the material being treated toward the center of the cylinder and thus cause it to pass through 75 the holes in the successive partitions.

While the material is thus being passed through the several partitions from one end 80 of the cylinder to the other, hot water is also fed into the cylinder by a pipe 18, controlled by a valve 19, the pipe 18 extending only into a terminal washing chamber 21 connected with the discharged end of the cylinder and co-axial therewith, from which 85 washing chamber 21 it flows into the cylinder, flowing through the openings in the partitions as the level of the water rises to and above said openings, and finally flowing 90 out through the feed opening 1 at the feed end of the cylinder.

In order to increase the leaching action of the water, it is additionally heated 95 in its progress through the leaching cylinder by means of steam pipes 22 of which there are as many as there are compartments in the leaching cylinder, said steam pipes being all inclosed within a tube 23 extending co-axially with the cylinder and being connected with transversely extending branch pipes 24, which extend downward a sufficient distance to discharge below the level of the water in the partitions, said branch pipes extending through holes 26 in the inclosing tube 23. The tube or casing 23 may be supported by any suitable means. It is here shown as suspended by hangers 28 from beams 29. The service performed by the casing 23 is to shed any of the material that 100 might drop thereon after being carried to the top of the chamber 2 and falling there-

from. If there were no protective covering to the steam pipes, such material, dropping on said pipes, might lodge therebetween and perhaps burn.

5 It is in order to insure that each compartment of the cylinder is properly heated and receives its proper amount of steam that the pipes 24 are maintained separate from each other and separately discharge steam into 10 the several compartments. And in order that the flow of steam to the several compartments may be regulated individually as desired, the pipes 22 are provided with individual valves 27.

15 The washing chamber 21 is to be regarded as a small compartment or extension of the cylinder in which the material is leached by pure water, and in which the flow of water is comparatively rapid.

20 I claim:—

1. In an apparatus of the character described, a rotatable cylindrical leaching chamber, having an opening at one end to feed thereinto material to be leached, means 25 for rotating said chamber, a longitudinal series of transverse annular partitions in said chamber, spaced apart to form compartments therein, diametrically opposite perforated shifter plates adjacent to each partition and oblique thereto, spaced at their outer edges from said partitions and extending at their inner edges through the central openings in said partitions, a

35 pipe for supplying water into the other end of said cylinder, a pipe for supplying steam to each compartment, and extending transversely of the cylinder to a distance outside the peripheries of the openings in the adjacent partitions, means for 40 individually controlling the flow of steam through said steam pipes, and a washing chamber secured at said other end around said pipes.

2. In an apparatus of the character described, a rotatable leaching chamber, having an opening at one end to feed thereinto material to be leached, means for rotating said chamber, a longitudinal series of transverse annular partitions in said chamber, spaced apart to form compartments therein, perforated shifter plates adjacent to said partitions and oblique thereto, spaced at 50 their outer edges from said partitions and extending at their inner edges through the central openings in said partitions, a pipe for supplying water into the other end of said cylinder, pipes for supplying steam through said other end, one for each compartment, and extending transversely of the compartments to a distance outside the peripheries of the openings in the adjacent partitions, and means for individually controlling the flow of steam through said steam pipes.

GUY S. DYER.
